OF LONDON, ENGLAND.

INK-FOUNTAIN FOR PRINTING-PRESSES.

1,105,690.

Specification of Letters Patent.

Patented Aug. 4, 1914.

Application filed July 22, 1912. Serial No. 710,885.

To all whom it may concern:

Be it known that we, HERBERT PEARCE, THOMAS ROBERT GILLETT PARKER, and FRED WESLEY WRIGHT, subjects of the King of the 5 United Kingdom of Great Britain and Ireland, residing at Linotype and Machinery Works, Broadheath, in the county of Chester, England, have invented new and useful Improved Ink-Fountains for Printing-Presses, of which the following is a 10 specification.

The present invention relates to improvements in a printing press ink fountain of the class that has a fountain back, a fountain frame, a fountain blade and a fountain roller.

It comprises improved means for adjusting the fountain blade as a whole relatively to the fountain roller in a direction parallel 20 or approximately so with the plane of the said blade and for taking up wear in the latter.

It comprises also improved means for allowing the entire fountain blade and entire 25 fountain back to be taken, as a whole, away from the fountain frame.

It comprises also improved means by which the fountain blade and fountain back can be taken, as a whole, away from the 30 fountain frame without disturbing the serpentine adjustment of the edge of the said blade, and can be put back again without damaging the said edge.

A preferred form of the several means 35 above enumerated, is illustrated in the accompanying drawings in which—

Figure 1 is a side elevation from the feeder side of the press; and Fig. 2, an elevation from the front end of the press, of 40 the right hand half of the said form. The left hand half is a replica of this right hand half.

Referring thereto, the fountain back 1 is adjustable upon the fountain frame 2 with 45 reference to the fountain roller 3, by an adjusting device at each end of it, the two devices being independent of each other. Each of these two devices consists, preferably, of a milled head screw 4 engaging in a front 50 to rear direction, in the fountain back 1 and having a pair of collars 5, 6, fast on it, and a slotted bracket or abutment 7 adapted to engage between the said collars and to be disengaged therefrom by being pivoted on

a pivot 8 projecting to the front and outside 55 the respective screw 4, from the respective end of the fountain frame 2. Consequently, the farther these screws 4 are screwed into the fountain back 1 when the brackets 7 are engaged with them, the farther will the edge 60 of the fountain blade 9 stand from the fountain roller 3. The pivots 8 may be replaced by set screws or their equivalent, engaging in the fountain frame 2 in such a way as to lock the brackets 7 when the latter are 65 engaged with their screws 4, to prevent any liability on the part of the said brackets to be disengaged from their screws when the latter are being turned. Thus referring to Fig. 2, 8 is to be taken as the head of a set 70 screw, the shank of which passes through the respective bracket 7 and engages in the fountain frame 2, thereby serving as the pivot of the said bracket, the head of the set screw serving to lock that bracket by being turned 75 into the said frame till it pinches the bracket between itself and the frame. There are two suitable grips 9^a symmetrically arranged on the fountain back 1 by which the attendant can easily move it and 80 the blade 9 from the fountain frame 2, after he has disengaged both the brackets 7 from the respective screws 4. Thus adjusting energy is applied to the blade at both ends of it and only to the ends of it, and to the 85 whole of it at once.

The fountain back 1 is locked to the frame 2 in its adjusted position on the latter, by a row of T-headed screws 10 passed up through front-to-rear slots 11 in the said 90 frame end screwed into the fountain back 1. Thus, the entire fountain blade and entire fountain back can be taken, as a whole, away from the fountain frame.

The edge of the fountain blade 9 has always been a spring one and the fountain frame 2 has had a row of set screws vertically adjustable in it for setting the respective portions of its edge up toward the roller 3 in a line other than parallel with 100 the surface of the said roller, and one which may be either at an angle with or serpentine with reference to it. If the back 1 and blade 3 were then moved away from the said roller, the edge of the blade would be moved 105 off the said set screws and would spring back to its normal line. Subsequent attempts to return the back and blade to their origi-

nal positions would damage the blade edge against the set screws. According to the present invention, the said row of set screws 12 work, not in the fountain frame 2, but 5 in the fountain back 1 and as the blade 9 is fast to the latter, no movement of the said blade from the roller 3 can move it off the screws 12, nor movement of it toward the said roller, damage its edge against them.

10 The fountain as a whole is adjustable upon the main frame 13 of the press, to and from the ink ductor roller 14 by an adjusting device at each side of the front end of the fountain frame 2, the two adjusting devices being independent of each other. This 15 position of the two adjusting devices and their independence of each other, is important, because it provides for the adjusting motion of the fountain being always parallel with the ductor roller. Each adjusting device consists, preferably, of a milled head screw 15 engaging in the fountain frame 2, lengthwise of the press, and having two 20 collars 16, 17, fast on its shank, and a slotted 25 bracket or abutment 18 fast to and projecting to the front from the respective side frame 13 of the press; the said screw 15, collars 16, 17, and bracket 18 being so positioned relatively to each other, that the 30 shank of a screw 15 turns in the slot in the bracket 18 and the two collars 16, 17, respectively bear against the front and rear faces of the said bracket.

Having described our invention, we declare that what we claim and desire to secure by Letters Patent is:—

1. The combination in an ink fountain having a fountain frame, a fountain blade,

and a fountain roller, of a fountain back adjustable upon the fountain frame relatively 40 to the fountain roller; an adjusting screw at each side of the fountain back and working in it along a line parallel with the adjusting motion of the said back upon the fountain frame; a pair of collars fast upon 45 each of the said screws; and an abutment carried by each side of the fountain frame, capable by being pivoted on the latter, of being engaged with the respective screw between its collars and of being disengaged 50 therefrom.

2. The combination in an ink fountain having a fountain frame, a fountain blade, and a fountain roller, of a fountain back adjustable upon the fountain frame relatively 55 to the fountain roller; an adjusting screw at each side of the fountain back and working in it along a line parallel with the adjusting motion of the said back upon the fountain frame; a pair of collars fast upon 60 each of the said screws; an abutment carried by each side of the fountain frame, capable by being pivoted on the latter, of being engaged with the respective screw between its collars and of being disengaged 65 therefrom; and means for locking each abutment in either of its two positions.

In witness whereof we have hereunto set our hands in the presence of two witnesses.

HERBERT PEARCE.

THOMAS ROBERT GILLETT PARKER.

FRED WESLEY WRIGHT.
